UNITED STATES PATENT OFFICE

92,265

DESIGN FOR A LOUD SPEAKER AND TABLE ASSEMBLY

Roger M. Newbold, Santa Monica, Calif.

Application March 12, 1934, Serial No. 51,024

Term of patent 7 years

To all whom it may concern:

Be it known that I, ROGER M. NEWBOLD, a citizen of the United States, residing at Santa Monica, in the county of Los Angeles, State of California, have invented a new, original, and ornamental Design for Loud Speaker and Table Assembly, of which the following is a specification, reference being had to the accompanying drawing, forming a part thereof.

The single figure of the drawing comprises a perspective view of a loud speaker and table assembly showing my new design.

I claim:

The ornamental design for a loud speaker and table assembly as shown.

Signed at Santa Monica, California, this 8th day of March, 1934.

ROGER M. NEWBOLD.
